ALOIS TEGELER, OF NASHUA, IOWA.

ADJUSTABLE WAGON-TONGUE HOUNDS.

1,313,967.

Specification of Letters Patent. Patented Aug. 26, 1919.

Application filed November 4, 1918. Serial No. 261,101.

To all whom it may concern:

Be it known that I, ALOIS TEGELER, a citizen of the United States, residing at Nashua, in the county of Chickasaw and State of Iowa, have invented new and useful Adjustable Wagon-Tongue Hounds, of which the following is a specification.

This invention relates to adjustable wagon tongue hounds, and more particularly to 10 that class having means for adjusting the same to fit between the hounds of the wagon.

An object is to provide means for causing the tongue-hounds to assume the same angular relation as the wagon-hounds so that, 15 when the tongue hounds are spread to fit between the wagon-hounds, the pull of the team is exerted along the entire length of the coacting hounds to move the load within the wagon, thus resulting in a distributed 20 strain on the several parts and insuring greater strength and durability thereto.

A further object is to provide hounds having the above characteristics, which are carried by and are inseparable from the tongue 25 of the wagon, thus avoiding any danger of loss of the parts, when the tongue is removed from the wagon to be stored or applied to another wagon.

A full and complete understanding of the 30 invention may be obtained from a consideration of the following detailed description, taken in connection with the accompanying drawing forming a part of this specification; it being understood that while the 35 drawing shows a practical form of the invention, the latter is not confined to strict conformity therewith, but may be changed or modified, so long as such changes or modifications mark no material departure from 40 the salient features of the invention, as specifically pointed out in the appended claim.

In the drawing, in which like reference 45 characters designate corresponding parts throughout the several figures:—

Figure 1 is a plan view of the invention, shown applied to the front hounds of a wagon of ordinary construction.

Fig. 2 is a transverse sectional view taken 50 on the line 2—2 of Fig. 1.

Fig. 3 is a similar view, taken on the line 3—3 of Fig. 1.

Fig. 4 is a longitudinal sectional view, taken on the line 4—4 of Fig. 1.

The front hounds 1—1 of a wagon are 55 illustrated in the drawing, and since these may represent the hounds of any wagon of ordinary construction, it is not deemed necessary to describe the same. The hounds are arranged at different angles and different 60 distances apart in wagons of different makes, and it is the object to arrange co-acting hounds carried by the tongue, so that the same may be readily adapted to properly fit the said wagon hounds. 65

To this end, the wagon-tongue 2, which may also be of any ordinary construction, is provided with a pair of oppositely disposed tongue-hounds 3—3, which are located adjacent to the rear or wagon end of the tongue 70 2 and at either side thereof, as clearly shown in Fig. 1 of the drawing. These tongue-hounds 3—3 are preferably formed of angle iron of ordinary commercial form, as shown, and are of sufficient weight and strength to 75 withstand the heavy strain to which they are subjected while in use. The plates or flanges of the angle iron, comprising the hounds, are arranged, one on the outside and one on top, so that the same may properly engage 80 the inner faces of the front wagon-hounds and at the same time have an inwardly-directed flange or plate for attachment to parts to be later described.

Front and rear spreader bars 4 and 5 respectively, connecting the hounds 3—3 and tongue 2 are pivotally mounted adjacent to their inner ends, upon the upper side of the tongue 2, the front and rear pivotal bolts 6 and 7 respectively traversing one of a series 85 of perforations 8, arranged longitudinally at the inner ends of said bars, which are arranged to lie one upon the other of each pair, the said bolts extending through suitable aligned, vertically-disposed passages 9, 90 formed in the longitudinal center of the wagon-tongue 2. These spreader bars 4 and 5 are similarly constructed except that the rear bars 5 are somewhat longer than the front bars 4 in order to conform to the tapering disposition of the wagon-hounds 1—1. 100 It is the ordinary practice to construct the wagon-hounds of lighter material than the wagon-tongue, and the upper face of the latter is therefore relatively higher than the 105 upper surfaces of the hounds, and since it is necessary that the adjustable tongue-hounds 3—3 shall bear firmly against the inner op-

posed faces of the wagon-hounds in order to properly function, the spreader bars 4 and 5 are each provided with a bend 10 adjacent to their outer ends, for the purpose of arranging the said ends beneath the horizontally disposed inwardly-directed flange of the adjacent hound 3, to which they are pivotally connected by vertically disposed bolts 11—11. The hounds are each provided near their front and rear ends with longitudinally disposed slots 12 formed in their inwardly-directed flanges for the reception of the said bolts 11—11, thus permitting of independent swinging movement of each of the spreader bars, as will be clearly understood, in order to secure the desired adjustment to fit the tongue-hound 3 to its adjacent co-acting wagon-hound 1. It will thus be seen that any forward or backward movement of any one of the spreaders about its pivot 6 or 7 will result in a corresponding inward or outward movement of the adjacent end of the tongue-hound.

The forward ends of the tongue-hounds are each pivotally connected by bolts 13 with the rear ends of drag links 14—14, which extend forwardly and inwardly toward the sides of the tongue 2, to which they are pivotally connected by vertically-disposed bolts 15 traversing eyes 16 formed in the rear ends of adjustable attaching plates 17, having suitable slots 18 for the reception of bolts 19, passing horizontally through the tongue 2, thus permitting the backward and forward adjustment of the attaching plates 17, as desired, to properly locate the hounds 3 with relation to the wagon-hounds 1—1. A clip 20 is suitably secured to the upper side of the wagon-tongue 2, to be used in connection with a double-tree (not shown).

The wagon-tongue 2 is provided with a passage-way 21 for the reception of the usual queen bolt 22 which is carried by the wagon-hounds 1—1, and the tongue-hounds 3—3 are provided with longitudinally disposed slots 23 formed in their vertical flanges, through which the said bolt 22 passes, in order to secure the tongue together with the parts carried thereby in position upon the wagon. The slots 23 permit of ample forward and backward movement of the hounds 3—3 during their adjustment. Filler blocks 24, preferably formed of wood, are secured by rivets 25 between the flanges of the hounds 3 and at the central portion thereof, and are provided with horizontally disposed slots 26, registering with and corresponding to the slots 23 and providing for the free passageway of the bolt 22 therethrough and the relative movement of the hounds 3—3 about said bolt.

It will be seen that by releasing the bolts 6, 7 and 11, and by the proper manipula-

tion of the spreaders 4 and 5, the hounds 3—3 may be brought to a position to snugly fit between the wagon-hounds 1—1, so that considerable of the strain on the queen bolt 22 will be relieved by such engagement, and it will also be seen that the drag links 14—14 tend to relieve such strain upon the bolt where passing through the wagon-tongue.

The hounds can be adjusted to fit any wagon in a short time. 75

In applying the same, the tongue is placed between the wagon-hounds with the tongue-hounds contracted. Then the queen bolt is passed transversely through the wagon-hounds, tongue and tongue-hounds. The front spreaders are then moved forwardly to force the engagement of the respective hounds and the rear spreaders are moved in like manner until the tongue-hounds snugly fit the wagon-hounds. The several bolts 85 are then tightened and the tongue is ready for use.

The slots in the tongue-hounds provide for ample movement of the queen bolt therethrough in order to adjust the said hounds to the wagon-hounds, and it will be seen, that by reason of the fact that all of the parts of the present device are formed of material readily found upon the market, the improved device may be cheaply 95 manufactured, that the same is strong and durable, and capable of being operated by anyone to adjust the tongue to any wagon of ordinary make.

Short pieces 13^a of angle-iron are riveted, 100 or otherwise secured, to the forward ends of the tongue-hounds 3—3, in a manner to provide horizontally disposed plates having suitable apertures for the reception of the lower ends of the bolts 13, for the purpose 105 of reinforcing the latter and supporting the rear ends of the links 14—14.

What is claimed is:

A device of the class described comprising a pair of spaced angle iron tongue-hounds arranged one on either side of a wagon-tongue adjacent to its rear end, drag links pivotally connecting the forward ends of said hounds to the sides of said tongue, said hounds having horizontal slots located 115 intermediate their ends for the reception of the queen bolt traversing the wagon-hounds and tongue, and also having longitudinally disposed slots near their respective front and rear ends, front and rear pairs of transverse spreader bars pivotally mounted at their inner ends and overlapping upon the wagon-tongue for horizontal swinging movement and arranged respectively in front and in rear of the queen bolt, and having their 120 outer ends each provided with a perforation adapted to register with a respective longitudinal slot in the spaced tongue-hounds,

and vertical bolts traversing the said slots and perforations, whereby when the said spreader bars are swung about their pivots upon the wagon-tongue, the adjacent ends 5 of said tongue-hounds are moved transversely thereof to adjust the same to the wagon-hounds.

In testimony that I claim the foregoing as my own I have hereto affixed my signature in the presence of two witnesses.

ALOIS TEGELER.
